DENTAL ORAL SUCTION DEVICE

W. Grant Johnson, 717 E. Chapman,
Orange, Calif. 92667

Filed Apr. 14, 1975, Ser. No. 567,780

Term of patent 14 years

Int. Cl. D24—02

U.S. Cl. D24—1 D

Fig. 1

Fig. 4

Fig. 2

Fig. 3

FIG. 1 is a perspective view of an oral suction device showing my new design;

FIG. 2 is a front elevational view thereof;

FIG. 3 is a side elevational view thereof; and

FIG. 4 is a rear elevational view thereof, the vacuum hose has been broken away to indicate indeterminate length.

I claim:

The ornamental design for a dental oral suction device, as shown and described.
